STOKER

Carleton K. Steins, Merion, Pa., assignor to The
Pennsylvania Railroad Company, Philadelphia,
Pa., a corporation of Pennsylvania

Application October 19, 1944, Serial No. 559,396

2 Claims. (Cl. 110—45)

1

This invention relates to stokers, that is to say, to devices for automatically feeding solid fuel into furnaces; and it is concerned more particularly with stokers intended for domestic use.

The chief aim of my invention is to provide a stoker of the sort referred to which is simple and compact; which is immune against easy disarrangement and therefore reliable in operation; which is efficient as regards fuel consumption; which is readily adaptable for position to suit different types of furnaces; and which, moreover, lends itself to economic production in quantity as considered both from the standpoint of the material required, and from the standpoint of the labor costs involved in its construction and in the assembling of its component parts.

Other objects and attendant advantages will appear from the following description of the attached drawings, wherein

Fig. 1 is a view, in side elevation, of a stoker conveniently embodying my invention showing the same in association with a hot water house-heating furnace which latter is fragmentarily illustrated in cross section.

Fig. 2 shows the elevation of the outer end of the stoker as it appears when viewed from the right of Fig. 1, with a portion of its fuel supply hopper partly broken out and in section.

Fig. 3 is a plan view of the organization shown in Fig. 1 with a cover of the supply hopper removed and portions of said hopper broken away to expose important details which would otherwise be hidden.

Fig. 4 is a fragmentary view in longitudinal section taken as indicated by the angled arrows IV—IV in Fig. 3.

Fig. 5 is a plan view of the portion of the stoker shown in Fig. 4, with certain parts drawn in horizontal section.

Fig. 6 is a fragmentary view in section taken as indicated by the angled arrows VI—VI in Fig. 3.

Fig. 7 is a fragmentary view in horizontal section taken as indicated by the angled arrows VII—VII in Fig. 2.

Fig. 8 is a fragmentary view in vertical section taken as indicated by the angled arrows VIII—VIII in Figs. 1 and 3; and

Fig. 9 is a detail section taken as indicated by the angled arrows IX—IX in Figs. 1 and 3.

With more specific reference to these illustrations, 10 designates a supply hopper for storage of finely comminuted solid fuel such, for example coal of buckwheat or rice sizes, said hopper being cylindric and having a frusto-conical bottom which terminates in a central gravity discharge opening. In addition to a tight fitting cover 11 the hopper is provided with a coarse mesh screen element 12 which is removably supported by a plurality of circumferentially spaced lugs 13 dis-

2

posed somewhat below the top edge of the hopper wall, and which is peripherally reinforced by a ring 15 of stout wire. Surrounding the discharge opening of the hopper 10 is a reinforcing outlet annulus 16 which is internally recessed as shown in Fig. 6 to fit over an annular seat 17 around the top inlet opening of a casting 18 to which it is secured by screws 16a (Figs. 1 and 4), said casting having a diametrically enlarged bell 19 at one end and a rearwardly-extending laterally-offset neck portion 20. Extending into the bore of the casting 18 at the bell end is a cylindric conduit 21 which is secured by set screws 22 (Figs. 4 and 5) and through which the fuel is conducted from the hopper 10, in a manner presently explained, to a burner 23 within the fire box of the hot water furnace which is comprehensively designated by the numeral 25 in Figs. 1 and 3. Surrounding the conduit 21 with provision of an annular interval 26, is a tube 27 of large diameter whereof the outer end fits into and is secured in the mouth of the bell end 19 of the casting 18 by set screws 28, said tube communicating with the passage in the offset portion 20 of said casting through which air is introduced under pressure, also as later on explained, to support combustion of the fuel in the furnace. From Figs. 1 and 3 it will be noted that the conduit 21 and the surrounding tube 27 extend into the fire box of the furnace 25 through an opening in the side wall of the latter, said opening being sealed air-tight around said tube by fire-proof packing 29 held in place by a backing member 30. The burner 23 previously referred to is in the form of a casting having upturned inner and outer elbow shells 31 and 32 which are respectively connected to the conduit 21 and the tube 27 by screws 31a and 32a (Fig. 5). As shown the inner shell 31 of the burner 23 is supplemented by an upwardly flared tuyère 33 of which the periphery rests in a recessed annular seat in the top of the outer shell while its lower end is engaged in an annular groove at the top of said shell, said tuyère being perforated and formed by a series of removable interlocking segments which are held down in place by a beveled cap ring 34 at the top of the burner and secured by screws 34a (Figs. 3 and 9). Disposed within the conduit 21 is a screw conveyer 35 by which the fuel is conducted from the storage hopper 10 to the burner 23, the shaft 36 of the screw conveyer passing through a bearing 37 set into the outer end of the bore of the casting 18. With its outlet neck connected to the offset passage 20 of the casting 18 by screws 20a (Figs. 3 and 5) is a centrifugal blower 40 which is cast en bloc with a shelf 41 whereon is supported an electric driving motor 42. As shown in Fig. 7, the shaft 43 of the blower rotor 44 is directly connected to the shaft 45 of the motor 42 through a coupling 46, while the

shaft 36 of the screw conveyer 35 is driven through speed reduction gearing within a casing 47 integrally formed with the housing of the blower 40 and the shelf 41. As shown, this gearing comprises a worm 48 on the blower shaft, and an inter-meshing worm wheel 49 which is secured to the upper end of a vertical shaft 50 and which in turn carries a worm 51 that meshes with a worm wheel 52 on the screw conveyer shaft 36. As shown in Fig. 8, the vertical shaft 50 is rotatively supported by bearings 53 and 54 whereof the former is integrally cast with the blower housing and of which the latter is provided by a closure cap 55 secured in an opening in the bottom of the housing 47. The screw conveyer shaft 36 extends into the interior of the housing 47 through an integral bearing 56 at one side of the latter and receives further rotative support in a separate bearing 57 provided by a cap 58 (Fig. 7) which closes an access opening 59 in the opposite side of said housing. For convenience of access to its interior, the gear housing 47 is provided with a removable cover 65. It is kept filled with oil to the level indicated at L in Fig. 8 so that the worm 51 and the wheel 52 as well as the bearings 53, 54 and 56, 57 for the shafts 50 and 36 are continuously lubricated. A disk 66 on the blower fan shaft 43 carries up oil from the supply in the housing 47 to a pendent distributing fin 67 on the cover 65 for conduction to the bearings 68 and 69 for said shaft. In order that the influx of air into the blower 40 may be regulated, there is provided a guard disk 70 which is adjustably supported by a screw bolt 71 engaged in the central boss 72 of a spider 73 within the air inlet opening 74 in the outer side of the blower casing.

The storage hopper 10 is supported from the floor by posts 75 which are adjustable in boss plates 76 bolted to the hopper bottom and securable in adjusted position by set screws shown at 77 in Figs. 1 and 2. The blower motor unit is similarly supported by posts 78 which are adjustable in lugs 79 and 80 formed on the blower casting and on the shelf 41 and which are securable in adjusted positions by set screws indicated at 81 and 82. Additional support is afforded the stoker by posts 83 adjustably engaged in the opposite ends of a transverse cradle bar 84 welded or otherwise secured to the bottom of the tube 27.

In the operation of the stoker, the fuel gravitating in the hopper 10 through the bottom outlet of the latter into the bowl portion of the casting 18 is advanced in the conduit 21 to the burner 23. At the same time the constant stream of air from the blower 40 is forced, by way of the offset 20 in the casting 18, into the annular clearance 26 within the tube 27 and around the conduit 21 into the space between the inner and outer shells 31 and 32 of the burner for diffusion and discharge into the fuel within the burner through the perforations in the tuyère 33. The gearing within the housing 47 is so proportioned that the screw conveyer 35 and the blower 40 are driven at relative speeds such that the burner 23 is kept filled with fuel and an adequate supply of air is furnished to insure complete combustion. As the fuel is consumed, the ashes are spilled over the edges of the cap ring 34 on the burner 23 into the ash pit at the bottom of the furnace, this movement of the ashes being facilitated by reason of the beveling of said cap ring 34.

From the foregoing it will be seen that due to

its compactness and simplicity my improved stoker can be produced and assembled at small cost and easily, and that it can be set up at the time of its installation for use with the furnace without necessitating the use of special tools or the employment of skilled help. Since both the screw conveyer and the blower 40 are driven from a single motor through gearing enclosed in a housing, and by reason of the fact provisions are made for self-lubrication of the moving parts within such housing, the stoker will require no attention whatever except for the renewal of the lubricant at long protracted intervals and for cleaning of the burner in case it should become clogged. Construction of the motor-supporting shelf integrally with the blower casing is advantageous in that the blower, the motor and the driving gearing can be assembled and produced as a unit at the factory. The stoker of my invention is further unique in that it does not require a pit at the furnace for its accommodation and in that it is bodily adjustable vertically and therefore easily adaptable to furnaces of different types.

Having thus described my invention, I claim:

1. A furnace stoker comprising a supply hopper for solid fuel, said hopper having a bottom with a forwardly-extending neck portion and a laterally-offset, rearwardly-extending communicating neck portion; an air-conducting tube connected to the forwardly-extending neck portion of the hopper bottom and leading to a burner within the furnace; a smaller fuel-conducting tube within the air-conducting tube connecting into the hopper bottom and also leading to said burner; a feed screw within the fuel-conducting tube having its shaft protruding through the hopper bottom at the rear; a motor driven blower with its casing connected to the rearwardly-extending neck portion of the hopper bottom; a motor for driving the blower; and speed reducing gearing interposed between the blower shaft and the fuel feed screw.

2. A furnace stoker comprising a supply hopper for solid fuel, said hopper having a bottom with a forwardly-extending neck portion, and a laterally-offset rearwardly-extending neck portion in communication with the forwardly-extending neck portion; an air conducting tube connected to the forwardly-extending neck portion of the hopper bottom and adapted to lead to a burner within the furnace; a smaller fuel conducting tube within the air conducting tube connecting into the hopper bottom and also leading to said burner; a feed screw within the fuel conducting tube having its shaft protruding through the hopper bottom at the rear; and a combined air supply and power unit including a blower fan having a casing with the outlet thereof connected to the rearwardly-extending neck portion of the hopper bottom, and a closed housing laterally offset from the casing through which the fan shaft extends horizontally, a motor directly connected to the protruding end of the fan shaft, a power shaft connected to the protruding end of the fuel feed screw aforesaid and extending into the housing, and speed reduction gearing within said housing interposed between said power shaft and said fan shaft whereby the feed screw is driven at reduced speed from said fan shaft.

CARLETON K. STEINS.
